his Attorney

UNITED STATES PATENT OFFICE.

HAROLD B. BARNES, OF DENVER, COLORADO.

AUDIBLE INDICATING DEVICE.

1,287,829.

Specification of Letters Patent. Patented Dec. 17, 1918.

Application filed February 24, 1917. Serial No. 150,736.

To all whom it may concern:

Be it known that I, HAROLD B. BARNES, a citizen of the United States, residing at city and county of Denver and State of Colorado, have invented certain new and useful Improvements in Audible Indicating Devices, of which the following is a specification.

My invention relates to an improvement 10 in audible indicating devices, and pertains more particularly to the so-called snap switch for controlling electric circuits.

With the present great advance in the art 15 of electric heaters and such like devices, wherein no light can be seen for the purpose of telling when the current has been turned on, such as is possible with an ordinary lamp, it has become important to provide a device whereby the snapping of the switch, 20 not only makes or breaks the circuit, and as is usual indicates the "on" or "off" position, but makes a sound sufficiently clear and distinct as to enable the operator to tell whether the switch is "on" or "off," even 25 though the switch itself cannot be seen, as when it is in a dark location.

Therefore, one of the objects of my invention is to produce such an audible indicating device, wherein different tones are produced, as it passes from one position to another.

A further object is in the provision of such a device in which the bell or other sound producer may be used to form the exterior cover for the switch.

Further advantages of my invention will become apparent in the specification and pointed out in the claims.

In the accompanying drawings which 40 form a part of the specification,

Figure 1 is a view in perspective showing my invention applied to an ordinary snap switch.

Fig. 2 is a vertical sectional view taken on 45 line 2-2 of Fig. 3.

Fig. 3 is a top plan view with some of the parts removed.

Fig. 4 is a view of a modified form, and

Fig. 5 is a detail perspective view of the 50 hammer and insulating means 15.

Fig. 6 is a detail showing the parts 13 and 16.

To the base 1 of an ordinary snap switch is connected a rotatable post 2 which carries 55 the usual circuit making arms 3-3 which engage the contact points 4-4 upon the actua-

tion of the snap button 5. To the arms 3-3 are rigidly attached tripping posts 6-6 adapted to turn with the arms.

Mounted on one side of the base 1 is a 60 plate 7, rigidly affixed. At one end of this plate 7 is pivotally mounted a bell crank lever 8 capable of oscillation about its pivot, but such action is against the pressure of the spring 8'. A hammer 9 is fastened to one 65 end of the bell crank lever, the other end terminating in a hook 10 adapted to be in the path of the tripping posts 6-6. A yoke 11 provided with a hole 12, is rigidly fastened to the base 1 at 13, 13 and carries a 70 threaded flanged hollow column 14.

In order to keep the insulated strip 15 in 75 position around the mechanism on the base 1, clamps 16 are fastened to the strap 11. A bell 17 provided with an orifice 18 is supported by the washer 19 on the strap 11, and is held in position by the nut 20. An opening 15' in the strip 15 permits the hammer 9 to pass through and strike the bell 17.

The stem 5' of the aforementioned snap 80 button 5 passes down through the opening in the column 14 and engages the top of the rotatable post 2. In the modified form, shown in Fig. 4, I have provided a plurality of bells nested one within the other for use 85 in a multiple point switch, such as can be used in an electric fan.

In this construction the outside bell extends down over the base, and a similar bell-crank 8 with its hammer 9 and hook 10 is 90 arranged below the contact mechanism and is actuated by an additional post 6' projecting downwardly from the actuating mechanism. The outside bell in this construction extends over the base and is struck 95 by the lower hammer, both bells being struck giving a signal when the switch is turned on or off.

In the operation of my invention, the snap button 5 is turned and through it the rotatable post 2 and the arms 3, 3 and the rigid tripping posts 6, 6. The arms 3, 3 rotate to the position shown in Fig. 3. When the snap is turned off, one of the arms 6 will engage the hook 10 on the bell crank levers 100 8 and cause same to oscillate about its pivot against the action of the spring 8'. This also causes the hammer 9 to be drawn in toward the center of the switch. As the tripping post 6 progresses in its trip to the "off" position, the hook 10 will be forced out of its path, and will slip off the rigid tripping post 105 110

6, permitting the spring 8' to return the bell crank lever 8 to its normal position causing the hammer 9 to deliver a sharp blow to the bell 17. This is thus capable of giving a 5 clear reverberating note by means of which it is possible to tell whether the switch is turned "on" or "off", regardless of whether visible means of obtaining such information is present or absent.

10 It is obvious that my invention produces a snap switch which is neat and artistic in appearance and efficient in action, which desirable objects are produced at a minimum of cost and labor. It is obvious that many 15 slight changes may be made without departing from the spirit and scope of my invention, but:

I claim—

1. In an audible indicating device, the combination with a base, of a supporting yoke mounted on said base, a rotatable post suspended therefrom, tripping-posts carried thereby, trip-actuated means mounted on said base and adapted to be actuated by said 25 tripping-posts, a bell-cover mounted on said yoke and surrounding mechanism of said device adapted to be struck by said trip-actuating mechanism upon the actuation of said rotatable post.
2. In an audible indicating device, the combination with a base, of a supporting yoke mounted on said base, a rotatable post suspended therefrom, circuit-making means carried by said post, trip-posts mounted on said 30 circuit-making means, trip-actuated means mounted on said base adapted to be actuated

by said trip-post, a bell-cover mounted on said yoke and surrounding the mechanism of said switch adapted to be struck by said trip-actuating means upon the actuation of said 40 rotatable post.

3. In an audible indicating device, the combination with a base, of a supporting yoke mounted on said base, a rotatable post suspended therefrom, circuit-making means 45 carried by said post, trip-posts mounted on said circuit-making means, trip-actuated means mounted on said base adapted to be actuated by said trip-post, an insulating band provided with an orifice surrounding 50 said mechanism and supported by said yoke, a bell covering mounted on said yoke and surrounding the mechanism of said switch, adapted to be struck by said trip-actuating means upon the actuation of said 55 rotatable post.

4. In an audible indicating device, the combination with a base, of a rotatable post mounted thereon, circuit making means carried by said post, tripping posts mounted on 60 said circuit making means, a plate mounted on the base, a lever pivotally mounted on said plate, one end of the lever provided with a hook and the other with a hammer, a bell cover mounted upon the base and surrounding the upper part of the switch, adapted to be struck by said hammer upon the actuation of the rotatable post and the consequent tripping of the hook on said bell 65 crank lever by said tripping post. 70

In testimony whereof I affix my signature.
HAROLD B. BARNES.
